UNITED STATES PATENT OFFICE.

ABRAM E. SMITH, OF HUGUENOT PARK, NEW YORK.

TANK CAR.

Original application filed February 23, 1921, Serial No. 447,178. Divided and this application filed June 7, 1922. Serial No. 566,511.

To all whom it may concern:

Be it known that I, ABRAM E. SMITH, a citizen of the United States, residing at Huguenot Park, in the county of Richmond 5 and State of New York, have invented certain new and useful Improvements in Tank Cars, of which the following is a specification.

My invention relates to tank cars, and particularly of that character or type generally employed for railway transportation of liquids in bulk, and which comprises a horizontally disposed cylindrical tank supported upon an underframe which, in turn, is 15 mounted on wheeled trucks.

The invention consists in the improvements to be more fully described hereinafter and the novelty of which will be particularly pointed out and distinctly claimed.

20 I have fully and clearly illustrated a preferred embodiment of my invention in the accompanying drawings to be taken as a part of this specification, and wherein Figure 1 is a view in side elevation of one embodiment of my invention and so much of a car structure as is necessary to illustrate the application of the invention thereto, certain parts of the car structure being omitted for the sake of clearness; Fig. 2 is 25 a detailed perspective view of a portion of the underframe of a car and showing means constituting my invention, for connecting a tank to the underframe in such manner as to prevent vertical movement of the tank relative to the underframe; Fig. 3 is a detail view showing the connection of Fig. 2 in 30 end elevation, and the preferred location of the same relative to the understructure, and Fig. 4 is a detail view in side elevation of 35 the connecting means shown in Fig. 2.

40 Before describing my invention in detail, I would state that while I have shown the same applied to a well known type of car underframe, I wish it understood that my invention is not limited to this type of underframe as it contemplates within its scope any type of underframe to which it may be applicable.

45 My present application is a division of my prior application Serial No. 447,178, which was filed in the United States Patent Office on or about February 23, 1921.

50 Referring to the drawings by characters of reference, 1 designates generally the underframe or understructure of a well-known

type of car, the same being shown as consisting of a center sill or structure 2 made up of structural iron consisting preferably of channel members or girders arranged with their body portions or webs 2' spaced 60 from each other in vertical parallel planes and with the side flanges 3, 4, thereof extending outwardly from the upper and lower edges of the webs. The vertical girder members described are connected by upper and 65 lower horizontal plates 5, 6, resting respectively on the outer faces of the flanges 3, 4, and secured rigidly thereto by means of rivets passing through the side edges of said plates and through said flanges, whereby a 70 rigid girder structure is provided. The said center sill extends preferably the entire length of the car and is connected at its ends to end sills 7 in any well-known manner (not shown). At its opposite ends the underframe is provided with suitable bolsters 8, 75 which may be of any suitable commercial type, for example, a built-up structure consisting of flanged vertical members 8^a secured at their inner ends to the center sill by 80 rivets or other suitable means, and at their outer ends to the longitudinal side members 9, said vertical members 8^a being connected by upper and lower horizontal plates 10, 11. The underframe is supported, in any suitable 85 manner, upon wheeled trucks (not shown) carrying running wheels 12 adapted to travel upon a railway track.

13 designates a tank body which may be of any suitable construction, the same being preferably cylindrical in form, and arranged over the underframe and adapted to rest on saddle blocks 7^a, which are in turn seated in saddle brackets 7^b secured to the bolster 8 (one of said saddles being shown, 90 in each of Figs. 2 and 3), the longitudinal axis of said tank extending longitudinally of said understructure. It will be understood that two saddles are employed on each bolster. For the sake of clearness the saddle 95 members have been omitted from Fig. 1 of the drawings. My invention contemplates improved and simplified means for connecting the tank body to the understructure, whereby the tank will be held at the point 100 of connection against longitudinal movement relative to the understructure, but which will permit ready installation of the tank in place on the underframe or removal therefrom. This means is preferably lo- 110

cated at the center portion of the tank body so as to act as an anchor for that portion and serve to permit longitudinal expansion and contraction of the opposite end portions of 5 the tank body relative to said connection. The details of the construction by which the tank body is secured to the underframe are more fully disclosed in my prior application above referred to, to which reference 10 is made for further details. Briefly, the construction comprises a plate secured to the underframe and secured to the tank body on both sides thereof. In Figure 1, the securing portion of the plate is shown on one 15 side at 23, the same being riveted to the tank body as at 24.

I provide improved means for securing the end portions of the tank body to the underframe, so as to limit or prevent vertical and 20 sidewise movement of the tank body relative to the underframe, but permitting longitudinal movement of the said end portions due to temperature changes. This connection in its preferred embodiment comprises 25 pairs of vertically disposed members 26, and located inside of the brackets 7^b, as best shown in Fig. 3, the members of each pair being arranged, respectively, in spaced relation, and in parallel planes extending trans- 30 versely of the underframe, and each of said members being connected to the underframe by a base flange 27 rigidly secured by rivets 28 to the cover plate 10 forming part of the bolster structure heretofore described. These 35 pairs of members 26 are located, respectively, on opposite sides of the longitudinal axis of the underframe, as clearly illustrated in Fig. 2 of the drawings. Secured to the under portion of the tank body at points over 40 the bolsters, are depending ears or lugs 29, each of which is integral with a securing member in the form of a flange 30, which is rigidly secured by means of rivets 31 to the tank body, whereby each of said members 45 29 is rigidly and immovably connected to the latter. The arrangement is such, therefore, that while the ends of the drum are free to move longitudinally, they are prevented from moving either laterally or 50 transversely. Each member 29 projects into the space between a pair of the members 26, and is of a thickness less than the width of said space, as clearly illustrated in Figs. 1 and 2, so that the member 29 may have suf- 55 ficient movement or play between the inner vertical faces of said members 26 when the tank body expands and contracts lengthwise of the underframe relative to the center connection. Each of the members 29 is 60 secured to its pair of securing members 26 by means of a cross bolt or pin 32 extending through alining openings in said members 26 and that portion of the member 29 arranged between said members 26 so that the mem- 65 ber 29 may move longitudinally of the un-

derframe, as heretofore described, but is held against vertical movement, thereby preventing vertical movement of the tank body relative to the underframe. The pins 32 are each preferably in the form of a headed bolt, the head 33 of which is located on the outer side of one of the members 26, and which bolt is held in place by means of cotter-pin 34 on the opposite end of said pin from the head and the outer side of the other member 26 of the pair. The hole in the member 29 through which the bolt projects is made large enough to permit free longitudinal movement of the tank body. This connection is not only simple and effective in structure, but eliminates the necessity of tank bands commonly used in tank car structure, and the disadvantages of which are well-known.

What I claim and desire to secure by Letters Patent of the United States is:—

1. In a tank car, an underframe, a tank body, and a connection between said tank body and underframe comprising spaced lugs on the underframe, and a lug on the tank extending between said spaced lugs and capable of movement therebetween lengthwise of the underframe, and means for securing the lug on the tank to said spaced lugs to prevent vertical movement of the tank relative to the underframe.

2. In a tank car, an underframe, a tank body, and a connection between said tank body and underframe, said connection comprising a pair of spaced vertical lugs carried by the underframe, and a lug carried by the tank body and located between said spaced lugs and capable of movement between the same lengthwise of the car body, and a connecting pin passing through all said lugs and extending lengthwise of the underframe.

3. In a tank car, an underframe including a center sill and bolsters, and a connection between said tank car and bolsters comprising a pair of spaced lugs mounted on the bolsters, and a lug on the tank body and projecting between said spaced lugs and capable of movement therebetween lengthwise of the underframe, and means for connecting all said lugs to prevent vertical movement of the tank body relative to the underframe.

4. In a tank car, an underframe, a tank body, and a connection between said tank body and underframe, said connection comprising a pair of spaced lugs connected to one of the said underframe and tank body, and a lug connected to the other of the same and projecting between said spaced lugs, said lugs and spaced lugs being spaced relative to each other to permit movement of the tank body lengthwise of the underframe, and means for connecting said lugs to prevent vertical movement of the tank body relative to the underframe.

5. In a tank car, an underframe compris-

ing a transverse bolster, a tank body, means for connecting said tank body to said under-frame comprising upwardly extending spaced lugs secured to the upper side of said 5 bolster, and a lug secured to the tank body and extending between said spaced lugs and means for connecting the tank lug to said spaced lugs, the parts being constructed and arranged to permit movement of said tank

10 lug longitudinally of the underframe, and prevent movement vertically thereof.

6. In a tank car, a tank body, an under-frame comprising a transverse bolster, saddles mounted one on either end of the bolster 15 for supporting the tank body, and means mounted within said saddles for connecting said tank body to said bolster and constructed and arranged to permit longitudinal movement and prevent vertical movement 20 of said tank body relatively to said underframe.

7. In a tank car, a tank body, an under-frame comprising a transverse bolster, saddles mounted one on either end of the bolster 25 for supporting the tank body, members se-

cured to the bolster inside of said saddles and comprising upwardly extending spaced lugs, and members secured to said tank body, and pivoted to said spaced lugs, the parts being constructed and arranged to permit 30 movement of said tank body longitudinally of said underframe and prevent vertical or transverse movement thereof.

8. In a tank car, a tank body, an under-frame comprising a transverse bolster, saddles mounted one on either end of the bolster 35 for supporting the tank body, members secured to the bolster inside of said saddles and comprising upwardly extending spaced lugs, and members secured to said tank body 40 and provided with lugs extending between and pivoted to said spaced lugs, a clearance being formed between said last-mentioned lugs and said upwardly extending lugs whereby the ends of said tank are free to 45 move longitudinally of said underframe, but are restrained from moving transversely thereof.

ABRAM E. SMITH.
